DOOR CHECK AND CLOSER

Andrew E. Kunzl, Marshall, Mich., assignor to
 Pittsburgh Plate Glass Company, Allegheny
 County, Pa., a corporation of Pennsylvania

Application August 21, 1947, Serial No. 769,912

3 Claims. (Cl. 16—55)

1

This invention relates to hinging door checks and closers for mounting and controlling swinging doors, and one of the principal objects of the invention is to provide an improved structure of cam and controlling mechanism by which force is applied directly to the hinge spindle of the door to yieldably resist swinging of the door to and from a predetermined position.

Another object of the invention is to provide an improved combination of cams, springs and dashpot action as applied to a hinge spindle of a door to control the swinging movement thereof.

In one form of the invention a floating piston having cam followers theron is mounted upon a hinge spindle which is formed with a cam track to receive the cam followers. Rotation of the spindle about a vertical axis moves the piston vertically in a bath of fluid, such as oil, which is enclosed in a chamber containing the mechanism, and, in conjunction with a dashpot arrangement, the movement of the piston is checked in one direction while it is permitted relatively free movement in the opposite direction. In other words, the door opens freely from a closed or dead center position and it is checked in returning to such position. Springs engage the piston on one side, and through a camming action, force is transmitted from the springs to the door to close it against the checking action of the dashpot arrangement.

In the drawings:

Fig. 1 is a fragmentary diagrammatic illustration of a door equipped with my improved door check and closer and the mountings therefor in a frame structure; Fig. 2 is a plan, on a large scale of a door checking and hinge mechanism; Fig. 3 is a vertical section taken substantially along the line III—III of Fig. 2; Fig. 4 is an irregular vertical section taken substantially along the line IV—IV of Fig. 2; Fig. 5 is a horizontal section taken substantially along the line V—V of Fig. 4; Fig. 6 is a diagrammatic plan of a development of a cam track included in the structure shown in the other figures of the drawing; and Fig. 7 is a fragmentary vertical section taken substantially along the line VII—VII of Fig. 2.

In practicing the invention a swinging door 10 is disposed vertically in a frame 12 in which upper and lower spindles 14 and 15 are vertically aligned to carry the door in its swinging motion in opposite directions about a vertical axis defined by the spindles. The lower cam spindle 15 constitutes a part of a door hinge and checking and closing mechanism 20 which includes a casing

21 mounted in a protective metal box 22. A rigid support 23, such as a part of a cement or concrete floor structure of a building, receives the box 22 rigidly set therein.

The casing 21 including its cover 24 encloses in fluid tight relation the working parts of the hinge and checking mechanism. The cover 24 is secured and centered upon the casing by means of screws 25 and dowel pins 26. Tongue and groove elements 28 interfit in conjunction with an interposed packing 29 (Fig. 4) are applied to insure a fluid tight seal between the cover and the casing.

Upper and lower ball bearings 30 and 31 are mounted in race rings 34 and 35, respectively, which are in turn centered in a cover opening 36 and upon a lower bearing plug 38. An opening 39 which is formed in a boss 40 in the bottom of the casing receives the bearing plug 38 rigidly therein and in fluid tight relation. The bottom of the cam spindle 15 is thus spaced by the boss and bearing structure from the area of the bottom of the casing surrounding the boss 40.

The cam spindle 15 which operates about a vertical axis upon the supporting bearings 30 and 31 is formed at its lower end with an annular rim or flange 41 within which the lower race rings 35 are fitted. The upper portion of the spindle 15 is surrounded by a stuffing box 42 designed to prevent escape of fluid 43 contained in the casing. This stuffing box is carried in a collar 44 that is screw threaded in the cover 24 to confine the upper bearing members 34 in proper position. The fluid 43 may be a suitable oil. The body portion of the cam spindle 15 is substantially cylindrical and is formed with an endless circumferential cam track or channel 45, a development of which is illustrated diagrammatically in Fig. 6. An annular block in the form of a piston 50 fits coaxially around the cam spindle 15 and is slidable vertically thereon. The inner cylindrical walls of the casing 21 and the outer cylindrical surface of the piston fit closely together in coaxial sliding relation. It is to be understood that the space between the outer surfaces of the spindle 15 and the inner cylindrical wall of the casing 21 constitutes an annular chamber 51 in which the piston 50 is vertically reciprocable.

Vertically disposed compression springs 52 having their lower ends confined in sockets 53 formed in the upper side of the piston are spaced 55 at various locations around the annular body

of the piston. The upper end of these springs are confined in sockets 54 formed in the lower side of the casing cover 24. These springs are installed under compression.

Vertical posts 58 and 59 (Fig. 3) are anchored at their lower ends, as indicated at 60, in the bottom of the casing 21 in fluid tight relation. Gaskets 61 surround the upper portions of the posts, and pressure rings 62 are fitted over reduced upper portions of the posts so as to rest upon shoulders 64 formed thereon. The gaskets are thus confined in recesses 65 in the casing cover to prevent leakage of fluid at this location. The upper portions of the posts are disposed in cover openings 66 so positioned as to insure vertical alignment of each post with respect to its upper and lower anchorage mountings. When the cover 24 is applied to the casing the gaskets 61 are compressed and the posts are thus secured in fluid tight relation with respect to the cover. Vertical openings 69 in the annular piston receive the posts in sliding relation so that the piston can reciprocate vertically, but is held against rotation.

Diametrically opposite bearing pins 80 are screw threaded, as indicated at 81, in the body of the piston and they are horizontally aligned in co-axial relation. Roller bearings 82 carried upon the inner ends of the pins support cam followers 83 which are in the form of rollers and are confined in the cam channel 45. The rollers 83 normally rest upon symmetrical lower cam sections 84 of the cam channel under the influence of the compression springs 52 which bear downwardly upon the piston 50. These lower cam sections communicate with similar higher cam sections 85 which are also on the lower wall of the cam channel. Upon rotation of the cam spindle 15 about the vertical axis the rollers 83 ride upon the lower wall of the channel 45 and are forced upwardly or downwardly depending upon the direction of rotation of the spindle and the position of the rollers in the cam track. In this way, movement of the piston 50, from any position depends upon rotation of the spindle 15. However, it is to be understood that from a dead center position of the rollers 83 the latter are forced upwardly in response to rotation of the spindle in either direction. The lower sections 84 of the cam channel are formed to correspond substantially to the curvature of the rollers 83 and there is appreciable space between the upper wall of the cam channel and the adjacent peripheral portion of each roller 83.

Humps 86 forming parts or extremities of the lower cam sections are traversed by the rollers 83 as the spindle is rotated in either direction from its normal or dead center position. Likewise, at the upper cam sections 85 similar humps 89 are provided between which portions of the peripheries of the rollers are respectively disposed. When the rollers are disposed in these sections appreciable force must be exerted in rotating the spindle in order to initiate movement of the rollers over the humps and thence to the other sections of the cam channel.

The lower spindle 15 is mounted rigidly on the door 10 which is capable of being swung on the spindle approximately 90° in either direction from its normally closed or dead center position. Until the door is opened it is maintained in its closed position by the pressure of the springs transmitted through the rollers 83 to the cam track while the rollers are resting in the lower cam sections 84. As the door begins to open the

rollers must first traverse the humps 86 in response to appreciably more force than that required to continue the swinging of the door to its open position. As the door approaches its extreme open position the rollers are forced over the humps 89 and the contour of the cam channel in the sections 85 is such that the door can be maintained in the extreme open positions by the resistance offered by these humps. However, only a slight degree of force applied to the door is necessary to start the door in its swinging movement back to its closed position under the influence of the force exerted by the springs 52.

In order to limit the movement of the door or to prevent over-swinging beyond its open position, as determined by the upper cam sections 85, a stop projection 90 is formed upon the lower rim 41 of the spindle 15. A stop plate 91 is disposed in the lower portion of the casing 21 and is provided with an anchoring lug 92 which fits into a recess 93 in the inner wall of the casing. Notched portions 94 of the plate fit closely about the lower end portions of the vertical posts 58 and 59 further to stabilize the plate and prevent accidental displacement thereof. Two stop shoulders 95 formed on the plate 91 are disposed in such position that the stop projection 90 strikes one or the other of these shoulders when the door 10 is swung to an open position.

In order to control the operation of the piston 50 under the influence of the operation of the springs 52 a dashpot action is provided in the chamber 51 in response to upward and downward movement of the piston. At least two of the sockets 53 of the annular piston communicate with the lower side of the piston through openings 100 in which one-way ball valves 101 are mounted. Each valve is held yieldably against a valve seat 102 by means of a coil spring 103 which is in turn held under compression by means of a tubular plug 104 screw threaded into the lower portion of the opening 100. It is to be understood that the fluid in the casing flows freely through each valved opening and through the tubular plug 104, when the piston 50 is moved from a lower position to an upper position, but the valve is closed and remains closed during downward movement of the piston. That is, the movement of the door in opening it is not materially resisted by the fluid flowing through the valved openings 100 as the cam spindle is rotated in either direction from the dead-center position indicated in Fig. 4.

Needle valves 105 and 106 are mounted in openings 108 and 109 formed longitudinally in the posts 58 and 59, respectively. Intermediate portions of these valves are screw threaded, as indicated at 112 and 113, in the posts 58 and 59, respectively. The upper portions of the needle valves are formed with circumferential channels 114 and 115 which receive packing rings 116 and 117 respectively. These packing rings provide fluid tight fitting of the upper ends of the needle valves in the openings 108 and 109.

Ducts 120 and 121 communicate through the walls of the hollow posts 58 and 59 with the upper area of the chamber 51 above the piston 50. Ducts 123 and 124 are formed vertically in the screw threaded portions of the needle valves to provide for fluid communicating between the upper and lower portions of the hollow posts 58 and 59, respectively. By adjusting the needle valve 105 vertically in response to turning it in its screw threaded mounting, the lower portion

can be positioned to open or close in varying degrees a duct 130 that communicates through the lower portion of the post with branching duct sections 131 formed vertically along the opposite sides of the post 51. The upper extremities of the duct sections 131 are located at least as high as the lower edge of the piston 50 in its upper position. Fluid can thus communicate through the post 58 from the upper to the lower sides of the piston 50 and the flow of such fluid is controlled by regulating the needle valve 105 which can be set as desired. During the entire movement of the piston from its upper position to its lower position the fluid will flow uniformly through the valved openings in the post 58, and in an amount determined by the adjustment of the needle valve.

The other needle valve 59 can be adjusted vertically to regulate the flow of fluid through a duct 135 in the lower portion of the post to permit the desired amount of fluid to flow from the upper to the lower side of the piston. A transverse duct section 136 communicating with the main duct 135 opens at its opposite extremities into the lower portion of the chamber 51 below the piston when the latter is in its upper position. When the door begins to close and the piston begins to move downwardly from its upward position fluid will flow relatively freely from the lower side of the piston to its upper side and the initial closing of the door will be relatively rapid. As soon as the lower edge of the piston slides past the transverse duct section 136 the flow of fluid through the valve openings in the post 59 is then substantially stopped and the speed of the closing door is reduced by the relatively limited flow of fluid permitted through the ducts 130 and 131 alone. The position of the transverse duct 136 is such that the door is checked to a very slow speed during the last 20° to 25° of its movement until it assumes a closed position. The speed of this final closing movement is determined by the amount of fluid permitted to flow through the ducts 130 and 131.

The protective metal supporting box 22 includes in its structure four upright corner posts 140 welded therein, as indicated at 141, to form a rigid supporting structure. The casing cover 24 overhangs the casing body 21 and is fastened securely to the protective box 22 by means of externally threaded leveling nuts 142 that are screw threaded into the casing cover 24 in such position as to rest upon the upper ends of the four corner posts 140. Locking screws 143 extend slidably through the leveling nuts 142 and are screw threaded into the upper end portions of the corner posts 140. By manipulating the nuts 142 and tightening the screws 143 to lock these nuts in adjusted positions, the assembled casing 21 and cover 24 can be positioned with precision for supporting the door 19.

A shielding plate 145 covers the casing cover 24 and is secured thereto by means of suitable screws 146. A dust shield in the form of a cap 148 fits around the upper portion of the spindle 15 and is fitted at its lower edge in an opening 149 in the shielding plate 145.

Although only an illustrative arrangement of structure embodying invention has been shown and described in detail it will be apparent to those skilled in the art that the invention is not so limited but that various changes can be made therein without departing from the spirit of the invention or the scope thereof as defined by the appended claims.

I claim:

1. In a door check structure, a casing having vertically aligned bearings therein and having upper and lower walls, a hinge spindle rotatable in said bearings and said spindle having a cam track disposed along the outer circumferential portion thereof, means for holding the spindle against axial displacement in the casing, said cam track having lower cam areas and upper cam areas, a pair of spaced upright posts anchored in stationary positions in the upper and lower walls of the casing, a block surrounding the spindle and being axially slidable in non-rotatable relation upon the upright posts, said block having thereon cam followers projecting inwardly from opposite directions onto the cam track and normally resting in the lower cam areas, anchoring means securing said followers on the block, a series of resilient members confined under compression between the upper sides of the block and the upper wall of the casing and yieldably resisting movement of the cam followers from the lower cam areas to the upper cam areas in response to turning of the spindle in its bearings.
2. In a door checking structure, a sealed fluid containing casing having upper and lower walls, a hinge spindle rotatable in said bearings and having a cam channel extending circumferentially thereon, said cam track having lower cam areas and upper cam areas, a pair of upright posts anchored in the upper and lower walls of the casing, a block surrounding the spindle and slidable upon the upright posts, said block including oppositely disposed cam followers normally disposed in the lower cam areas and movable to the higher cam areas in response to rotation of the spindle in either direction, said posts having valved ducts extending therethrough and communicating through the upright posts from upper to the lower sides of the block for a passage of fluid in the casing from one side of the block to the other, valve members exposed on the outside of the casing and being selectively operable in said ducts to regulate the passage of fluid therethrough, a one-way valve communicating from the upper to the lower side of the block at a location spaced from the posts, and a series of resilient members confined under compression between the upper side of the block and the upper wall of the casing and resisting movement of the cam followers from the lower cam areas to the upper cam areas in response to the turning of the spindle in either direction in its bearings.
3. In a door checking structure a sealed fluid containing casing having upper and lower walls, a hinge spindle rotatable in said bearings and having a cam channel extending circumferentially thereon, said cam track having lower cam areas and upper cam areas, a pair of upright posts anchored in the upper and lower walls of the casing, a block surrounding the spindle and slidable upon the upright posts, said block including oppositely disposed cam followers normally disposed in the lower cam areas and movable to the higher cam areas in response to rotation of the spindle in either direction, valved ducts leading from upper to the lower sides of the block through the upright posts for a passage of fluid in the casing from one side of the block to the other, a one-way valve communicating from the upper to the lower side of the block at a location spaced from the posts, and a series of resilient members confined under compression between the upper side of the block and the upper

wall of the casing and resisting movement of the cam followers from the lower cam areas to the higher cam areas in response to the turning of the spindle in either direction in its bearings; said ducts having sections terminating at different distances from the bottom of the casing to regulate the degree of checking action of the block as the latter moves toward the bottom of the casing.
